UNITED STATES PATENT OFFICE

2,543,044

VAPORIZING TYPE OIL BURNER UNIT

Jacob R. Moon, Columbus, Ga.

Application June 24, 1946, Serial No. 678,831

1 Claim. (Cl. 158—91)

1

The invention relates to a burner unit and more especially to an oil burner unit for a furnace, stove or the like.

The primary object of the invention is to provide a unit of this character, wherein the same can be installed within a furnace, stove or the like, so that oil can be used as fuel with economy in consumption and resultant maximum heating qualities, the unit being of novel construction, and unique in assembly.

Another object of the invention is to provide a unit of this character, wherein natural air is supplied thereto for proper combustion of the fuel oil, the latter being vaporized by the heat of the fire box or basin and burned without smoking.

A further object of the invention is to provide a unit of this character, wherein it will burn any kind of oil, regular fuel oil, crude oil, kerosene, crankcase oil, etc., with minimum quantity required, for heating purposes.

A still further object of the invention is to provide a unit of this character, which is simple in construction, thoroughly reliable and efficient in operation, strong, durable, readily and easily installed, possessed of few parts, thus economical for repairs and replacements, assured of maximum heating quality and inexpensive to manufacture and install.

With these and other objects in view the invention consists in the features of construction, combination and arrangement of parts as will be hereinafter more fully described, illustrated in the accompanying drawings, which disclose the preferred and modified forms of construction, and pointed out in the claim hereunto appended.

In the accompanying drawings:

Figure 1 is an elevation of a furnace, partly broken away, showing the oil burner unit constructed in accordance with the invention installed.

Figure 2 is a sectional view taken on the line 2—2 of Figure 1 looking in the direction of the arrows.

Figure 3 is a sectional view taken on the line 3—3 of Figure 1 looking in the direction of the arrows.

Figure 4 is a sectional view taken on the line 4—4 of Figure 1 looking in the direction of the arrows.

Figure 5 is an enlarged vertical sectional view through the unit.

Similar reference characters indicate corresponding parts throughout the several views in the drawings.

2

Referring to the drawings in detail, particularly Figures 1 to 5 inclusive, which is the preferred embodiment of the invention, A designates generally a greater portion of a hot air furnace, yet it may be of any other type and as usual has a cylindrical shell or casing 10 provided in the lower portion thereof with a pit 11, above which is disposed a refractory flame basin 12 having a cup-shaped or bowl formation 13, provided with 10 a stepped annular wall 14 having troughs indicated at 15. This basin 12 at the periphery has contact with the shell or casing 10, and is at rest upon a supporting ledge 16 built with such casing or shell, as best seen in Figure 1 of the drawings, to be held in a horizontal plane therein.

The basin 12 centrally thereof is provided with a vertical passage, in which is snugly fitted a perpendicular tubular flue 17 providing an air inlet course from the pit 11, and the upper end 20 of the flue is provided with a burner hood 18 having a convexed top surface 19. Depending from the under face of the hood is a pair of spaced annular ribs 20 and 21 respectively, the rib 20 being deeper than the rib 21. The ribs are positioned over the trough formations 15. The flue 17 exteriorly thereof is provided with a stop flange 22 which seats against the flooring of the bowl 13 and thus the hood 18 is substantially level with the uppermost portion of the basin 12. The 30 ribs depending from the hood 18 coact with troughs 15 to define a tortuous path for the passage therethrough of the products of combustion.

The flue 17 is provided with vents 23 forming air outlets to the bowl formation 13, while opening into the latter is an oil supply pipe 24, which is passed vertically through the basin 12 and has union at 25 with a delivery pipe 26 leading from an oil supply tank 27, which has hanger connection 28 with a water reservoir 29 mounted upon 35 the shell or casing 10 exteriorly thereof, as best seen in Figure 1 of the drawings. This pipe 26 is provided with an oil feed regulating control 30 which is located in a discharge spout 31 unitary with the bottom of the tank 27.

45 What is claimed is:

In a fuel burner unit, a shell, a basin arranged in said shell and provided with a cup-shaped combustion bowl, there being a plurality of circular troughs arranged in said bowl, the outer periphery of said bowl being arranged in contact with the interior of said shell, a horizontally disposed ledge projecting inwardly from said shell for supporting said basin, there being a central passage in said basin, a first vertically disposed 55 pipe extending through the passage in said basin

for conveying air to said bowl, a second vertically disposed pipe extending through said basin and arranged adjacent one side thereof for conveying fuel from a source of supply to said bowl, a circular hood mounted on said first pipe and having a conical top surface, a plurality of spaced ribs depending from the under surface of said hood and coacting with said troughs to define a tortuous path for the passage therethrough of the products of combustion, the innermost ribs being longer than the outermost ribs, a horizontally disposed stop flange projecting outwardly from said first pipe and abutting said basin, there being a plurality of air vents in said first vertically disposed pipe.
